W. E. Kennedy,
By his Attorney,
G. L. Chapin

United States Patent Office.

W. E. CANEDY, OF WAUCONDA, ILLINOIS.

Letters Patent No. 91,519, dated June 22, 1869.

IMPROVED STOVE-PIPE SHELF AND DRIER.

The Schedule referred to in these Letters Patent and making part of the same.

To all whom it may concern:

Be it known that I, W. E. CANEDY, of Wauconda, in the county of Lake, and State of Illinois, have invented a Combined Shelf, Fruit-Drier, and Clothes-Drier; and I do hereby declare that the following is a full, clear, and exact description thereof, which will enable others skilled in the art to make and use the same, reference being had to the accompanying drawings, and letters marked thereon, making a part of this description, in which—

Figure 1 is a perspective representation of my invention.

Figure 2, a broken view of the under side, showing the folding leaf, and the manner in which it is held in a plane with the shelf.

Figure 3, a vertical section, taken through fig. 1 on the line Z.

Figure 4, a perspective view of the device for supporting the leaf and the arms of the clothes-drier.

Figure 5, a view of one of the inner angles of the fruit-drier, showing the rod that holds it together.

The nature of the present invention consists in the novel construction and combination of a rotating shelf, a drying or warming-oven, and a clothes-drier, the whole being supported in a convenient position above a stove by the pipe leading therefrom.

R represents a light iron shelf, which is cast in a solid plate or with intersecting bars and scroll-work, as most desirable, and which has a circular opening through it of suitable size to receive a collar, L, figs. 1 and 3, on which the shelf rotates.

This collar has a flange, M, fig. 3, on which the shelf bears, and over its periphery, at the top end, is placed a collar, N, which is held in place by means of a screw, V, passing through projecting lugs on the collars, and bearing against a curved plate, x, and at the same time holding the collar L to the stove-pipe A.

The shelf R at one side of the pipe supports a dry-

ing and warming-oven, D, which consists of a top plate, D, ends and back H I, doors F, and a grated bottom, J J, &c., the several parts being held together by means of rods E put through the shelf R, and fastened to the grated bottom J. In making the article, however, the plate D may be dispensed with by casting the top part R solid, and using it as a top for the drier.

A leaf, B, figs. 1, 2, and 3, is hinged to the shelf R at O C, and it is supported by a truncated support, K, which is so cut away at g that when that side is turned around, on its pivot l, to a point parallel with the joint of the leaf, the latter will fall down, as shown by dotted lines O, fig. 1.

This support is arranged, by means of slots f f, &c., to hold a series of arms, P, for drying clothes, or other household articles, and therefore the double purpose of supporting the leaf B and arms P.

By means of this construction and arrangement the drier can be placed on the front, back, or side of the pipe A, according to the degree of heat required, and if the room in front of the pipe is required for culinary purposes, the leaf B can be turned down.

Having thus described my invention,

I do not claim a stove-pipe shelf, that having been used before; but

What I do claim, and desire to secure by Letters Patent of the United States, is—

The combination of a rotating shelf, R, provided with a hinged leaf, B, with the drying-oven D, provided with a grated bottom, J, and the pivoted support K, provided with slots f, for supporting arms P, and so cut away on the side g as to allow the leaf B to fall down, when the support is turned on its pivot l, as set forth.

W. E. CANEDY.
